Specification for Design.

Patented Sept. 13, 1921.

Application filed January 10, 1921. Serial No. 436,362. Term of patent 14 years.

To all whom it may concern:

Be it known that I, CHARLES TWEEDIE, a citizen of the United States, and a resident of Jefferson City, county of Cole, and State of Missouri, have invented a new, original, and ornamental Design for a Boot-Top, of which the following is a specification.

In the accompanying drawing, which forms part of this specification.

The figure is a side view of the boot top embodying the design, the boot top being shown in position on a shoe which is indicated in dotted lines.

I claim:

The ornamental design for a boot top, as shown.

CHARLES TWEEDIE.
